CRANK AND GEAR CASE CLEANING
APPARATUS

James K. Delano, New York, N. Y.

Application November 21, 1934, Serial No. 754,025

3 Claims. (Cl. 184—1.5)

The invention described herein is for the purpose of cleaning the crank-case pans of internal combustion engines and especially engines which have compartments formed by baffles built into the lower part of the crank-case pan, the baffles being for the purpose of preventing the too rapid transfer of the oil supply from one end of the pan to the other and when the vehicle is inclined, as in climbing up or going down a grade, and to prevent splashing or surging on starting or stopping quickly.

The average automobile of today has the crank-case pan divided into several compartments by partitions, baffles or bulkheads which fit fairly close to the sides and bottom of the pan, but which are not oil tight, and in some cases these partitions have a top to which they are secured and which divides the pan into an upper and a lower compartment, the lower compartment being subdivided into compartments by the partitions thus dividing up the lubricant which is contained therein.

The drain opening is usually placed either at one end in the bottom of the pan or upon one side, and it is almost an impossibility to remove the sediment which forms from the wear of the engine parts and the breaking down of the oil under heat, etc., by draining the pan as the heavy sediment is prevented from draining out by the baffle plates and collects upon the bottom and in the corners of the separate compartments.

Filling the pan with a light oil and running the engine does not agitate this sediment as the connecting rods in the modern engine do not dip into the lower compartment of the pan, hence when draining, only a small part of the dirt is removed and a large percentage is left behind to mix with any fresh lubricating oil and gradually by the running of the engine for a few days to contaminate the new oil with the left over sediment resulting in greatly reducing its value as a lubricant.

The sediment in the average engine consists of carbon, grit, finely divided metal, such as iron, steel, babbitt, road dirt, etc., and an oil sludge which is a heavy bodied mixture caused by atmospheric condensation in the crank-case, and it is highly important that at no time during the cleaning operation when once this sediment is agitated and mixed with the cleaning fluid, that it be allowed to settle.

Due to the bottom of the pan being practically level there is no tendency for the sediment to drain out by natural flow.

Devices have been made for the purpose of cleaning the pan by employing a cleaning fluid under pressure and injecting this into the crank-case and these devices do very well when the stream of fluid can be directed against the sediment, but it is almost an impossibility to get at any part of the pan except where the nozzle of the cleaner is inserted, hence these types of cleaners do a good job on one compartment only and cannot reach the sediment in the other compartment.

Other types of cleaners circulating a cleaning fluid into the crank-case by putting it into the filler pipe and draining it out at the drain plug opening, but this method only cleans a short path between where it enters and the drain opening and does not reach the deposits of sediment which have collected back of the baffle plates.

In other devices for this purpose where cleaning fluid is injected into the crank-case through the drain hole and then sucked out again, this being accomplished either by a double acting pump, or one pump for injecting the liquid and another pump for drawing it out, the direction of flow of the liquid through the pump or pumps is governed by manually operated valves placed in the pipe line, but in such devices depending upon the operator, the action can not be quick enough to prevent the settlement of the sediment in the crank-case between the injections and withdrawal.

In such devices the operator must be in constant attendance working the controls and should the pressure be misjudged and one of the valves remain closed the apparatus will become damaged. It is also highly important that the injection and withdrawal cycle be operated as fast as possible to prevent the stirred up heavy bodied sediment from settling.

To produce the desired results with such a push and pull system it must be accurately timed so that the removal of the fluid takes place immediately after the completion of the injection and before the sediment has time to settle, and from the first injection until all of the fluid has been removed from the crank-case the sediment must be kept agitated and kept in motion not only to prevent settlement but to loosen and wash away the remaining adhering sediment.

By the use of a proper motor either A. C. or D. C. constant speed can be maintained and by knowledge of the pump capacity and quantity of fluid required, and the proper gear ratios the operation of the device will be accurately timed and no loss of time take place between injections and withdrawal.

drawals, except the lapse of time which is provided for the fluid to function as provided.

As an illustration of the difficulties encountered in cleaning out the deposit from pans which are formed with baffle plates and divided into compartments, some of which are also closed at the top, would be to take a small heap of dirt and place it upon a saucer and invert over this a tin can, and then try to remove the dirt from under the can by directing a stream of water into the saucer, and it will be seen that it is almost impossible to reach and dislodge the dirt and wash it away from under the can.

To take care of these conditions, I have worked out a method and apparatus by which I can agitate and wash out the deposited sediment within the compartments formed by the baffle plates in the pan, by causing the cleaning fluid to have a "tidal" flow between the several compartments of the pan, and I have illustrated this method in the drawings in a graphic manner with views showing the condition of the pan upon the different steps of the process.

The object of the invention is to provide both a method and apparatus for carrying out the same which will surely and quickly dislodge and remove the dirt and sediment which has collected in the compartments formed in a crank-case pan.

Another object of the invention being to provide in such a device automatic timed means whereby upon the completion of each injection of liquid into the crank-case pan it is instantly removed and the loosened sediment carried with it.

Another object of the invention is to provide means whereby the liquid is cleaned between each injection.

Another object being to provide means whereby the liquid is heated before each injection into the pan.

With these and other objects in view, the invention consists in certain novel construction and combination of parts as will hereinafter be fully described and claimed, and further illustrated in the accompanying drawings which form a part hereof and in which like figures of reference refer to corresponding parts in all of the views, and it is understood that slight changes may be made without departing from the spirit of the invention.

I do not deem it necessary to describe and illustrate in detail each part of the apparatus employed as several different constructions may be used, and I have therefore in the drawings shown the apparatus in schematic form and wiring diagrams to illustrate the electric installation required.

In the drawings:

Figure 1 is a diagrammatical view showing a sectional view of an automobile crank-case pan having baffle plates and indicating the sediment in the bottom of the pan and against the baffle plates and also indicating the cylinder and piston or one form of my apparatus. In this view, the cylinder has a charge of cleaning fluid; the piston is in its raised position and the service hose is entered into the drain opening of the pan.

Figures 2, 3, 4, and 5 are similar views, but showing the conditions existing under different stages of the injection and suction strokes, and how the sediment is loosened and removed.

Figure 6 indicates a cross sectional view of the crank-case pan, to further illustrate the location of the baffle plates.

In Figure 3 of the drawings it is shown where the fluid in the several compartments of the

crankcase has reached its level in all compartments.

Time is given for this flow of fluid to pass the baffle plates, by the piston 20 having reached the bottom of the injection stroke. As there is very little movement at the two extremes of the stroke, there is a pause given to the flow of fluid at these two points allowing a small period of time to allow the fluid to equalize its levels in the several compartments of the crankcase.

Figure 7 shows a diagrammatical view of one form of apparatus for carrying out my invention; some of the parts being shown in section.

Figure 8 is a wiring diagram showing the electrical installation required to operate this form of the apparatus.

Figure 9 is an enlarged detail view partly in section of one end of the wiper arms.

Figure 10 is an enlarged detail view partly in section of the air valve.

Figure 11 is a diagrammatical view of another form of apparatus for carrying out my invention.

Figure 12 shows the wiring diagram for the same.

Figure 13 is a vertical sectional view of the kind of apparatus that would be employed to carry out the idea as indicated in Figure 11.

Figure 14 is a schematic view of the rotary valve. Referring to the drawings:

In Figures 1 to 5 inclusive, I have illustrated the crank-case pan of a well known make of automobile which shows the baffle plates 11 and the cover plate 12 which is formed with the depressions 13, and this illustrates the usual type of divided pan to form compartments 14.

In these figures I have indicated a part of my apparatus comprising a pump cylinder 15 which is designed to hold a supply of cleaning fluid 16, and this cylinder 15 is connected by a service hose 17 and nozzle 18 to a bushing attached to the drain opening 19 of the crank-case pan 10.

In Figure 1, the piston 20 of the pump 15 is shown at the top of its stroke and the pump filled with the fluid; no injection having been made as yet, but the old lubricant having been drained out leaving the sediment as indicated.

In Figure 2, the piston is shown as having made a part of its downward or injection stroke and a part of the liquid has been forced through the pipe 17 into the central compartment 14 of the pan; 50 the level of liquid raising quickly in this central compartment and flowing through the small openings between the baffle plates 11 and the sides and bottom of the pan 10 into the adjacent compartments, as indicated by the arrow heads. Some of 55 the liquid passing through the deposited sediment dislodging the same and washing and mixing it into the body of the fluid.

In Figure 3, the injection stroke has been completed and all of the fluid has been injected into 60 the pan 10 and has reached its level in all of the compartments 14.

In Figure 4 is shown the piston starting upward on the suction stroke, which follows instantly upon the completion of the injection stroke, and it will be seen that the liquid is first exhausted or sucked from the central compartment 14 and the level in this compartment is lowered before the level in the adjacent compartments, as the liquid has to pass from these adjacent compartments 70 into the central compartment through the small opening between the baffle plates 11 and the sides and bottom of the pan 10 before entering the central compartment 14 and thus out through the pipe 17. The sediment lodged in the cracks and 75

corners is thus washed with the liquid into the central compartment for removal.

In Figure 5 is shown the piston 20 upon the completion of its suction stroke having drawn all of the liquid and sediment from the pan 10 into the pump 15. This cycle of operation being repeated a predetermined number of times and without any pause between the injection and suction strokes thus keeping the liquid in constant motion with a back and forth surge from one compartment to the other which will dislodge the sediment and dirt and not allow it time within which to settle before being sucked out, and it is this action of creating the different liquid levels which causes the tidal action from one compartment to the other through the cracks and seams that scours out the deposits of sediment.

Referring to Figure 7 of the drawings in which I have shown a diagrammatical view of an apparatus for carrying out the steps of my invention, I have added means for cleaning the liquid after each removal from the crank-case pan, and also means for heating the liquid before each injection into the pan, although both of these steps may be eliminated if desired.

In this drawing, I have shown the pump cylinder 15 and the piston 20; while said piston 20 is reciprocated by the connecting rod 21 pivoted thereto and to a gear wheel 22 which is in mesh with and rotated by a pinion 23 on a shaft 24 upon which is secured a gear wheel 25 in mesh with and rotated by a worm 26 mounted on a motor shaft 27 of the motor 28.

Said pump 15 is provided with an inlet 29 from a supply tank 30 having a filler pipe 31 and cover 32; while within said tank 30 is mounted a float 33 which operates a valve 34 in the bottom of said tank, and to the float 33 is attached a cable 35 from the indicator level gage 36; while the bottom of the pump 15 is provided with an outlet pipe 37, T 38 and drain pipe 39 having the cock 40.

The bottom of the tank 30 is connected to the T 38 by a pipe 41 within which is located a check valve 42, and from this same T 38 a pipe 43 leads to the bottom of a heater 44, and from the top of said heater 44 a flow pipe 45 conveys the liquid through a check valve 46 and T 47 to the service pipe 48 with its nozzle 49.

The heater 44 is provided with an electrical heating element 49 and a thermostatic control 205.

By the use of a centrifuge there is no delayed flow to pump which is the case where cloth or other types of filters are employed for removal of the dirt, as they become clogged up and impede the flow. Also by cleaning the interior of the centrifuge after each completed cleaning operation the caked and packed sediment being removed, I have provided a device that will operate at high efficiency.

This liquid cleaner comprises a two part casing 50 and 51 secured together as at 52 and formed with the aligned bearings 53 and 54 within which are rotatably mounted the upper and lower tubular necks 55 and 56 of a centrifuge 57; the upper neck 55 having secured thereon a spur gear 58 which is in mesh with and rotated by a spur gear 59 secured on the lower end of the motor shaft 27, which is rotatably mounted in a bearing 60 formed in the upper casing 50.

Above and communicating with the neck 55 is a duct 61 which is attached by a pipe 62 and check valve 63 to the lower end of the heater 44.

The lower casing part 51 is also formed with a

duct 65 communicating with the lower neck 56 of the centrifuge 57 and this duct is attached by a pipe 64 to the T fitting 47.

The lower casing 51 adjacent to and communicating with the duct 65 is provided with a valve 66 and a tubular boss 67 within which is slidably mounted a valve stem 68 having a head 69 for engagement with the valve seat 66; while the tubular boss 67 is provided with the drain pipe 70.

Adjacent to the lower end of the tubular boss 10 67 is placed an air vent valve 71 having the port 72 (see Figure 10) and a piston 73 to the end of which is pivoted the arm or lever 74 which is pivoted as at 75 to the casing boss 67 and also has pivoted thereto the outer end of the valve stem 15 68; the valve 66 being retained normally open by the action of the spring 76 mounted on said stem 68; the lever 74 being actuated by an electrical magnet or relay 77 as shown. These valves could be operated either manually or mechanically, if 20 desired.

The port 72 of the air valve 71 is for admitting air through the small pipe 78 and the pipe 62 to the upper part of the centrifuge during the operation of draining of the same.

For dislodging and removing the caked and deposited dirt and sediment from the corners of the centrifuge 57, I have provided the shaft 80 which is freely rotatably mounted in the pivot bearings 81 and 82 formed in the casing parts 50 30 and 51; and upon this shaft 80 is secured a wheel 83 to which are secured a number of scraper bent wires 84 (see Figure 9).

The purpose of this being that after the rotation of the centrifuge 57 has been stopped, the 35 wheel and scrapers, due to the momentum of the wheel 83 will continue to rotate at high speed and the scrapers 84 will remove the deposit and allow it to pass off with the liquid through the neck 56 and drain 10.

The timing of the operations of the apparatus is controlled by a ratchet 90, which should have the same number of teeth as the number of strokes required by the piston 20 to complete one cleaning cycle. This ratchet 90 being rotated one tooth 45 at a time by a finger 91 on the upper end of the connecting rod 21, so that for each revolution of the gear 22 the ratchet 90 is rotated one tooth, and this ratchet 90 is provided with a cam arm 92 that will upon each complete revolution of the 50 ratchet 90, strike a bumper 93 mounted on an arm 94 having an electrical contact 95 cooperating with the contact 96, the circuit being momentarily broken when the last suction stroke is complete and all of the fluid is out of the crank-case.

Referring to the wiring diagram shown in Figure 8, by turning "on" the button 102 of the main switch the current is brought in by the mains 100 and 101 through the switch contacts 103 and 60 104 into and through the resistance 107 and the timer contacts 95 and 96 to the main 100. Also the magnet coil 112 and through the wire 108 to the wire 109.

As the coil 112 is in series with the motor 28 65 and it closes the contacts 110 and 111 of the coil 112, the push button 102 may now be released by the operator as there is enough current going through the resistance 107 to feed the coil 112. The current passing from the main 70 100 through the switch contacts 95 and 96 and resistance 107 and through the contacts 113 and 114 (which are normally closed) to and through the coil 112 to the wire 109, and through the closed contacts 110 and 111 to the main 101, which 75

- causes the motor 28 to rotate, and by the wires 115 and 116 closes the valve 66 and also starts the heater 44; the thermostat 205 being normally closed.
- 5 When the timer arm 92 strikes the contact bumper 94 the contacts 95 and 96 are opened and the circuit broken through the coil 112 so that the contacts 110 and 111 open and every thing stops and the flushing operation is completed.
- 10 It is very important that when this stoppage takes place the pump piston 20 be at the extreme of its up stroke so that the fluid can enter the cylinder through the duct 29 to again fill the cylinder.

- 15 Due to the momentum of the motor shaft 27 and centrifuge 57 the trip arm 92 will pass the bumper 93 allowing the contacts 95 and 96 to close, but the drive operation can not be started up again without pushing the "on" button, because the relay 112 has opened the circuit.
- 20 The operation of the machine may be stopped at any time by pushing in the "off" button 120 which opens the circuit of the coil 112 and the contacts 110 and 111. Also should the heater 44 become too hot the thermostat 205 will break the 25 circuit through its contacts and stop the heating circuit.

30 In the operation of this embodiment of my device as shown in Figure 7, the tank 30 is filled with fluid through the filler 31 and the float 33 raises and opens the valve 34, but due to the valve 42 having a spring check the liquid does not pass through this valve to the cylinder but flows through the duct 29 as the piston 20 is in its raised position so that the duct 29 is open, any 35 liquid overflow from the piston 20 being carried through the pipe 207 to the top of the piston 20 and so back through the duct 29. The total capacity of both the supply tank and the pump as here indicated is three gallons, but which can be 40 varied as desired, and of this total amount the pump 15 holds two gallons and the supply tank 30, holds one gallon. The overflow pipe 207 is used to convey excess oil from the cylinder 15 to the top of the piston 20 and so back to the tank 30 45 through the duct 29.

To start the cleaning operation, press the "on" button 102, closing the circuit to the motor 28 and rotating the gears 26, 25, 23, and 22 which will reciprocate the connecting rod 21 and the piston 50 20 downward and inject the two gallons of fluid through the pipes 41 and 43 to the heater 44 and from there by the pipe 45 through the check valve 46 to the service hose 18 and so through the nozzle 48 into the crank-case 10, and as the circuit to the heater is closed, hot fluid is injected 55 at its highest temperature as the heated oil does not have to pass through the pump or other parts of the system.

60 On the up or suction stroke of the piston 20, which follows immediately after the injection stroke is completed, the two gallons of liquid plus what dirt, sediment, etc., has mixed with it while in the crank-case pan 10, are sucked out through the nozzle 48, service hose 18 and pipes 17 and 65 64 to the duct 65 and up through the tubular neck 56 into and through the centrifuge 57, passing out through the upper neck 55, pipe 62 and check valve 63 to the pipe 43 back to the bottom of the pump 15 and so into the same.

70 As the liquid is passing up through the centrifuge 57 which is being rotated at high speed through the gears 58 and 59 from the motor shaft 27, the dirt, heavy particles, etc., contained in the liquid will, through the centrifugal action, be 75 thrown to and remain in the outer periphery of

the centrifuge 57, while the cleaner liquid will pass upward and back to the pump 15 as stated, leaving one gallon of the liquid in the centrifuge 57 on this suction stroke; while at the same time some of the liquid in the tank 30 has gone through the valve 34, pipe 41 and check 42 into the pump 15 to the amount of about one-half gallon.

80 During the injection stroke, which is now repeated, about one and one-half gallons are injected, and upon the suction stroke the other one-half gallon is put into action; the float 33 dropping to close the valve 34 to prevent any air from entering the pump 15, and in this way two gallons is in operation and that passing through the heater just before entering the crank-case is 15 always at its hottest upon entering the crank-case pan.

10 The construction illustrated in Figures 11 and 13 differs from that shown in Figure 7, in that in place of employing a reciprocating pump for 20 causing the injections and withdrawals, I have employed a rotary pump in connection with a special valve through which the fluid is passed in both the injection and withdrawal direction, the direction of flow through this valve being 25 changed and timed in an automatic manner so that after the predetermined quantity of fluid has been injected into the crank-case, the valve will be operated to reverse the direction of flow of fluid so that the withdrawal will take place.

30 I have also provided an overriding clutch located between the motor shaft and the centrifuge so that for a period of time after the motor and pump have been stopped the centrifuge will continue to rotate for the purpose of cleaning the 35 same by the means provided.

40 Also in this model I have introduced an electrically operated brake for instantly stopping the rotation of the motor shaft after the current supply has been cut off. However this could be accomplished in other ways than that shown.

45 In carrying out the method illustrated in these Figures 11 and 13, I have indicated an electrical motor 28 having a shaft 27 to the lower end of which is attached a rotary pump 130 mounted 45 below the casing 131.

50 Rotatably mounted on this shaft 27 is the centrifuge 57 by the bearing 132; the lower end of this bearing being formed with a clutch member 133 that engages with a clutch member 134 secured to the shaft 27 in such a manner that the shaft 27 will rotate the centrifuge 57 in one direction only and when the shaft 27 is stopped the centrifuge 57 will continue to rotate for a short time.

55 The upper end of the centrifuge 57 is formed with a tubular neck 135 through which the fluid is entered by the spout 136 of the supply tank 137 which is filled in the usual manner through the filler 206 and which may be provided with 60 a liquid level gage if desired.

65 The centrifuge 57 is surrounded by an inner casing 139 which is formed with a sump 140, and this inner casing 139 and sump 140 are enclosed in an outer casing 141 forming a fluid chamber between the walls of the casings 139 and 141; the upper part of the centrifuge 57 has a splash collar 142 and the outlet holes 143 through the sides thereof, while the ducts 144 communicate with the ducts 105 in the top thereof.

70 Below the centrifuge 57 and located in the chamber formed by the casings 139 and 141 are located the resistance heating elements 145 by which the fluid is heated.

75 A four-way rotary valve 150 is indicated and 75

this is operated to change the direction of flow therethrough by a shaft 151 to which is attached a timing device for actuating said valve at predetermined times, and this valve is connected 5 by the pipes 152 and 153 to the intake and outlet ports of the pump 130, and by the pipe 154 to the bottom of the fluid chamber 155, and by the pipe 156 to the service hose 18.

Between the valve 150 and the chamber 155 the 10 pipe 154 is provided with a T fitting 157 from which a pipe 158 leads to the tank 137; while between the fitting 157 and the tank 137 is placed a check valve 162, and between the bottom of the chamber 155 and the fitting 157 is placed a check 15 valve 163.

A stand pipe 159 is also provided for the chamber 155 and this is fitted with a sight level gage 160.

The timing mechanism for operating the valve 20 150 to reverse the flow therethrough at predetermined times, comprises a bevel gear 165 secured on the motor shaft 27 in mesh with and driving a bevel gear 166 mounted on a shaft 167. On the end of shaft 151 is mounted a bevel gear 25 168 which is in mesh with and is driven by either of the two bevel gears 172 and 173 which are freely rotatably mounted on the shaft 167.

This shaft 167 is squared or splined in its central portion and slidably mounted thereon is a 30 clutch member 170 which is formed with the clutch teeth on both ends adapted to engage with the clutch teeth 171 formed on the gears 172 and 173 for the purpose of rotating the shaft 151 in either direction.

35 For imparting a sliding movement in either direction to the clutch member 170, an arm 174 is provided having a forked end to engage an annular groove in the member 170; this arm 174 being pivoted as at 175 and provided with a 40 stud 106.

For shifting this timing clutch at predetermined intervals a worm 177 is mounted on the valve shaft 151 in mesh with a worm wheel 178, and on this wheel 178 is pivoted one end of 45 a connecting rod 180, the other end being formed with an edge 181 which engages the teeth of a ratchet 176 which is mounted on a shaft 169 on which is placed a disk 161 having a notch 188 for the bumper 121 of a contact arm 182 having 50 the contacts 183 and 184. It will thus be seen that as the ratchet wheel 176 and the cam or disk 161 are both secured upon the shaft 169 that as the worm wheel 178 is rotated, the arm 180 engaging the teeth of the ratchet 176 will rotate 55 the same tooth by tooth and thus rotate the disk 161, which when the notch 188 registers with the bumper 121 will allow the contacts 183 and 184 to separate.

A vertical arm 189 has its lower end pivoted 60 as at 300, and is also pivoted at 185 to the arm 180 and at 301 to the arm 190 and is formed with a pointed end 186 for engagement with a spring actuated plunger 187 to effect a quick change from side to side. The arm 190 is formed 65 with a slot to engage with the stud 106 to move the clutch arm 174.

In the designing of this apparatus it is important that the ratio of the worm 177 and wheel 178 be so that there is time allowed for the fluid 70 from the tank 137 to completely drain into the centrifuge 57 and also to permit the complete drainage of the crank-case pan 10.

Also the ratchet 176 is so designed that by the rotation of the disk 161, the bumper 121 on the 75 arm 182 will break the contacts 183 and 184 and

stop the machine after the last withdrawal stroke.

The clutch 200 is of the usual friction type, and therefore, when the pins 200 and 203 contact together, the lower part of the shaft 151 will become stationary, and the upper part of the same 5 shaft will continue to rotate.

The electrically operated brake 191 on the motor shaft is operated by the magnet 192 and comes on when the magnet releases.

Referring to Figure 12, the wiring diagram is 10 shown for the construction shown in Figure 11. The two mains 193 and 194 are indicated; the main 193 leading to the thermostat 205 on the heater, while the main 194 leads through the switch 195 to the other terminal of the heater 15 145. A circuit being made to the motor 28 by the wires 196 and 197, and to the brake 191 by the wires 198 and 199; while between the main 194 and the timer disk 161 is placed the contact arm 182 and contacts 183 and 184, so that when the 20 main circuit is closed by the switch 195 the motor will start, the magnet be energized to release the brake 191 and the heater 145 be operated; while at the same time through the gearing, the disk 161 will rotate by the action of the arm 180 and 25 the wheel 176 while the contacts 183 and 184 remain closed, until the bumper 121 reaches the notch 188 when the contacts 183 and 184 will open and the circuit be opened.

In the operation of the apparatus shown in 30 Figures 11 and 13, the operator puts three gallons of cleaning fluid into the tank 155 through the filler pipe 159; the quantity of fluid being indicated by the sight gage 160.

The crank-case having been drained of old oil, 35 the service hose 18 is attached thereto in some suitable manner and the operator closes the switch 195 of the current mains to energize the motor 28 and also to release the brake 191 and to generate heat in the resistance element 145 of 40 the heater which is immersed in the tank 155.

The pump 130 is operated through the rotation of the motor shaft 27 direct and through the ratchet clutch 133 the centrifuge 57 is rotated at 45 high speed.

Assuming that the four-way valve 150 is in the proper position, the fluid will be pumped from the tank 155 through the check valve 163 and pipe 154 to the valve 150, and through the ports in said valve 150 and pipe 156 and hose 18 to the 50 crank-case.

At the same time that this is being done, the gears 165 and 166 are being driven by the shaft 27 and the bevel gears 172 and 173 (either of which is engaged with the clutch 170) driving the 55 bevel gear on the worm shaft 151 and through the friction clutch 200 operating the valve 150 to change the direction of flow therethrough.

After the worm wheel 178 which is rotated by 60 the worm on the shaft 151 makes a predetermined part of a revolution it causes the lever 189 to move by the link 190 the shift lever 174 and clutch member 170 into reverse engagement with the gear 173, which causes the shaft 151 to reverse 65 its direction of rotation.

This causes the pump 130 by the reversal of the valve 150 to withdraw the fluid from the crank-case 10 by the hose 18, pipe 156, through the valve 150 and through pipe 154 and check valve 162 70 and pipe 158 to the tank 137.

As this returned fluid from the crank-case has mixed with it dirt, etc., it is carried by gravity flow from the tank 137 and spout 136 into the neck 75 135 of the centrifuge 57 which it will fill to the

level of the holes 143, through which it will overflow into the tank 155. The centrifuge in this case holding about one gallon of the fluid.

It is to be noted that the check valves 162 and 183 direct the flow to and from the tank 155.

The suction and pressure periods of the fluid are timed by the mechanism through the gear 178 so that they have a definite time between reversals of direction of flow due to the over riding 10 spring actuated snap device as shown at 186 and 187, which assists the quick shifting of the clutch member 170.

The oscillating worm wheel 178 is also employed to operate the ratchet 176, until the disk 161 on 15 the shaft 169 makes one complete revolution so that the contacts 183 and 184 are broken after one revolution of this disk.

These contacts 183 and 184 being wired on the main feed circuit will when opened cause 20 the stopping of the apparatus, and also by this opening of circuit the magnetic brake 192 is de-energized causing the brake to operate and stop the rotating of the motor shaft 27 but allowing the centrifuge 57 to continue to rotate for 25 some time.

The rotary valve 150 has a drive by the pins 202 and 203 which allows some lost motion in its operation to give the pump 130 time to allow for complete drainage from the crank-case before 30 reversal of the flow, and also to allow for drainage of the fluid from tank 137 to tank 155.

The number of teeth in the ratchet 176 determine the length of time for the cleaning period.

It is to be noted that after the centrifuge 57 35 has retained one gallon of fluid out of the three gallons that was put in to start with, that two gallons are used in the cleaning operation. Upon the stopping of the apparatus by the opening of the contacts 183 and 184, the centrifuge 57, due 40 to its momentum, will continue to rotate for a short time and is free to rotate due to the clutch 183. The motor shaft 27 having been stopped by opening of the current and by the operation of the magnetic brake 191.

45 The scrapers 84 will thus stand still while the centrifuge rotates about them and in this manner the heavy deposit of dirt, etc., upon the inner periphery of the centrifuge 57 will be removed and mix with the fluid therein.

50 As soon as the rotative speed of the centrifuge 57 is reduced sufficiently, the fluid therein, together with the accumulated dirt, will drop to the bottom and into the sump 140, where it will pass off through the drain pipe 70.

55 It is to be noted that the fluid contained in

the tank 155 is always being subjected to heat from the resistance elements 145.

Upon starting up the apparatus for the next cleaning operation, it is only necessary to add one gallon of fluid to the tank 155 to replace the gallon of used fluid that has been removed from the centrifuge 57.

Having thus described my invention, what I claim as new and desire to secure by Letters Patent, is:

1. In a crank-case cleaning apparatus having a pumping member adapted to contain a fluid supply and a tubular connection for conveying the fluid to the crank-case, of automatic means for injecting a predetermined quantity of the fluid 15 into the crank-case and withdrawing the same immediately, automatic means for repeating the injections and withdrawals for a predetermined number of times, and automatic means for ceasing the operations when the last of the predetermined number of withdrawals of fluid is completed.

2. In a crank-case cleaning apparatus having a pumping member adapted to hold a fluid supply and a connection for conveying the fluid to the 25 crank-case, of automatic means for heating the fluid within the apparatus, automatic means for regulating the degree of heat, automatic means for injecting the heated fluid into the crank-case, automatic means for immediately withdrawing 30 the fluid from the crank-case, automatic means for returning the fluid to the apparatus, automatic means for treating the fluid to remove the dirt therefrom, automatic means for repeating the 35 injections and withdrawals for a predetermined number of times, and automatic means for stopping the operations of the apparatus upon the last withdrawal of fluid from the crank-case.

3. In a crank-case cleaning apparatus having a pumping member adapted to hold a fluid supply 40 and a tubular connection for conveying the fluid to the crank-case, of electrical means for heating the fluid within the apparatus, automatic means for retaining a portion of the fluid within the apparatus, automatic means for injecting the 45 remainder of the fluid into the crank-case in a predetermined number of injections, automatic means for withdrawing each injection from the crank-case and returning it to the apparatus, automatic means for cleaning the fluid after each 50 withdrawal from the crank-case, and automatic means for stopping the operations of the apparatus after the final injection has been withdrawn from the crank-case.

JAMES K. DELANO. 55
